[57] CLAIM

The ornamental design for hutch, as shown and described.

DESCRIPTION

FIG. 1 is a perspective view of a hutch embodying our new design;

FIG. 2 is a front elevational view thereof;

FIG. 3 is an end elevational view, with the opposite end thereof being a mirror image thereof; and,

FIG. 4 is a top plan view thereof. The bottom and rear of the hutch are unornamented.
